US0D1075778S

(12) **United States Design Patent** (10) **Patent No.:** **US D1,075,778 S**
(45) **Date of Patent:** **** May 20, 2025**

(54) **GAMEPAD PROTECTIVE SLEEVE**

(71) Applicant: **Shenzhen Lidacheng Technology Co., Ltd.**, Shenzhen (CN)

(72) Inventor: **Jincheng Wu**, Shenzhen (CN)

(73) Assignee: **Shenzhen Lidacheng Technology Co., Ltd.**, Shenzhen (CN)

(**) Term: **15 Years**

(21) Appl. No.: **29/981,773**

(22) Filed: **Jan. 2, 2025**

(30) **Foreign Application Priority Data**

Dec. 7, 2024 (CN) 202430778776.0

(51) **LOC (15) Cl.** **03-01**

(52) **U.S. Cl.**

USPC **D14/454**; D21/333

(57) **CLAIM**

The ornamental design for a gamepad protective sleeve, as shown and described.

DESCRIPTION

FIG. 1 is a front perspective view of a gamepad protective sleeve, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the gamepad protective sleeve which form no part of the claimed design.

1 Claim, 8 Drawing Sheets
